FRANS IVAR L. BYLGER, OF JERSEY CITY, NEW JERSEY.

ROTARY ENGINE.

1,376,397.

Specification of Letters Patent.

Patented May 3, 1921.

Application filed December 29, 1915, Serial No. 69,166. Renewed September 22, 1920. Serial No. 412,086.

To all whom it may concern:

Be it known that I, FRANS IVAR LEANDER BYLGER, a citizen of the United States, residing at Jersey City, county of Hudson, 5 and State of New Jersey, have invented certain new and useful Improvements in Rotary Engines, of which the following is a specification.

This invention relates to rotary engines of the type having a working chamber, the side walls of which are formed by surfaces of cones rolling in contact, the chamber being completed by an inclosing shell. In engines of this type, blades or pistons are employed 10 which are carried by or rotate with the cones and which cross the working chamber and form movable abutments for the steam or working fluid to act upon. A fixed abutment which sustains the reaction of the 15 working fluid is formed by the line of contact between the cones and which, although the cones themselves revolve, remains stationary. Engines of this type possess the important advantage that the contact between parts subjected to heavy pressures is 20 a rolling contact, and the resulting resistance and wear therefore much less than if a sliding contact existed. Numerous attempts have heretofore been made to employ the 25 principle of rolling cones in rotary engines, but the advantages of the broad principle of operation involved have been largely lost through mechanical difficulties caused by the manner of mounting the blades or pistons. 30 This has been in large part due to the fact that in all prior engines of this type, so far as I am aware, the attempt has been made to make the common apex of the cones the center of rotation of the entire system, the 35 inclosing shell being a spherical surface with this common apex as a center and the axis of rotation of the blades passing through this same point. In one prior type of engine of this character the blades have had 40 sliding connection with one or both of the cones and pivotal connection with both of the cones, the axes of the pivotal connections passing through the common apex of the cones. This arrangement is not satisfactory 45 for the reason that it does not permit the blades or pistons to be attached to the central hub or shell if true rolling contact is to be obtained, and therefore a solid mounting 50 of the pistons, which are the parts upon which the force of the operating fluid is directly expended, is not possible. The piv-

otal and sliding joints between the pistons and cones have also been made to transmit the power of the engine, a duty which they are not well adapted to perform. Another 60 attempt to solve the problem has been by the use of blades jointed or hinged in the middle, a highly unsatisfactory construction from a practical point of view as it does not permit of the blades being adequately supported and it also introduces serious problems in the way of preventing leakage. Another way of solving the problem is by making the blade revolve about the axis of one of the cones. This is the method which I 65 have adopted in my two prior Patents, Numbers 1,091,806 and 1,056,400, the constructions disclosed in which permit true 70 rolling contact between the cones to be achieved, and while superior to prior constructions, necessitate the use of certain mechanical details more or less difficult to make and to keep in permanent and satisfactory 75 operative condition.

The object of my present invention is to 80 produce a rotary engine securing the advantages of the principle of employing rolling cones in a simplified, strong, durable and efficient structure. I have discovered that this object may be accomplished by 85 constructing the engine so that the main axis of rotation is displaced from the common apex of the cones and in which the cones do not work in a spherical shell having as its center, the common apex of the cones, but in 90 which the shell has two spherical surfaces, the centers of which are the respective points of intersection of the axes of the cones with the main axis of rotation of the system. With this construction it is possible to 95 utilize a rigid blade or piston having a pivotal connection with each cone, the axes of the pivotal joints passing through the respective points of intersection of the axes of the cones with the main axis of rotation of 100 the system, so that the blades lie in planes passing through such main axis of rotation at all times, while the axes of the pivotal connections between the blades and cones at all times pass through the respective axes of 105 rotation of the cones. As a result of this, it is possible to mount the blades rigidly as a part of a main rotor which includes the inclosing shell and the central hub or member upon which the conical elements are 110 mounted and which may be carried upon the main shaft of the engine, the axis of

which will coincide with the main axis of rotation of the system. At the same time permanent rolling contact is maintained at all times between the conical surfaces. Further objects of my invention include the balancing of pressures upon the conical members and improvements of various details of construction, as will more fully appear from the following detailed description 10 of one preferred embodiment of my invention.

While I have referred and will refer throughout this specification and claims to my invention as an "engine" this term is to be understood in its broader sense as it is obvious that my invention is applicable to pumps, compressors and the like, as well as to prime movers. Likewise, while the specification refers specifically to the use of steam 20 as an operating fluid, it is to be understood that any other suitable operating fluid may be used in the case of a prime mover, while the device may be used as a compressor or pump for any fluid or liquid capable of being passed through the same.

In the accompanying drawings, which form a part of this specification, Figure 1 is a vertical longitudinal sectional view through an engine embodying my invention, 30 parts being shown in elevation. Fig. 2 is a section on line II—II of Fig. 1. Fig. 3 is a section on line III—III of Fig. 1. Fig. 4 is a vertical sectional view through a part of the engine, the rotors being shown revolved 35 90° from the position shown in Fig. 1. Fig. 5 is a section on line V—V of Fig. 4. Fig. 6 is a fragmentary sectional view on line VI—VI of Fig. 4.

Referring to the drawings in detail, the 40 numeral 1 designates the bed-plate of the engine upon which are mounted the pillars 2, carrying the main bearings 3 for the main shaft 4 of the engine and also carrying the inclined bearings 5 for the secondary rotors 45 6. The secondary rotors have conical surfaces 7 which roll in contact along the fixed contact line 8. These surfaces constitute portions of the surfaces of cones having a common apex indicated by the point O and 50 the axes of which, indicated by the lines OA and OB, respectively, are perpendicular to the planes of the bearings 5. As illustrated, the secondary rotors 6 comprise the conical faced ring members 9, which are secured to 55 the carrying rings 10 by suitable means such as screws 11. The carrying rings 10 are connected to or formed integral with sleeves 12 of reduced diameter and are provided with openings 13 for a purpose which will 60 be hereinafter explained.

In the drawings the bearings 5 are illustrated as ball bearings, a series of balls 14 being mounted between the fixed races 15, attached to the pillars 2 and the rotatable 65 races 16 which are mounted upon the sleeves

12. This type of bearing is very satisfactory especially for engines of the smaller sizes. Obviously, however, any other suitable type of bearing for supporting the secondary rotors may be employed. The secondary 70 rotors are provided with the concave spherical surfaces 17 and the convex spherical surfaces 18 and 19, all of these surfaces for each secondary rotor being concentric.

Mounted on the main shaft 4 is a hub 20, 75 which is provided with a pair of spherical surfaces 21, which fit the spherical surfaces 17 of the respective rotors. Inclosing the outer ring portions of the secondary rotors is a shell 22 having concave spherical surfaces 23 fitting the convex spherical surfaces 18 and the concentric concave spherical surfaces 24 fitting the spherical surface 19 of the secondary rotors. The common centers of all the spherical surfaces of each secondary rotor and of the engaging spherical surfaces of the hub and shell are the points E and F, which are the points of intersection of the axes OA and OB of the respective conical surfaces, with the axis CD of 85 the main shaft of the engine. It will be seen that the conical surfaces 7, portions of the spherical surfaces 21 of the hub 20, and portions of the spherical surfaces 23 of the shell 22 inclose a chamber 25 which constitutes the main working chamber of the engine, the width of this chamber being greatest at the top and decreasing to nothing at the line of contact 8, where the conical surfaces touch.

The chamber is crossed and divided into parts by one or more blades or pistons 26, two arranged at diametrically opposite points being shown in the construction illustrated. (See Figs. 1, 4 and 5). These blades 105 or pistons are preferably firmly secured to the hub 20, in any suitable manner, for instance, by being driven into grooves 27 formed therein and are also suitably secured to the shell 22, for instance as by being secured between the sections thereof by the bolts 28 (see Fig. 5). The blades or pistons thus firmly unite the hub 20 and shell 22 and cause them to rotate together, additional means being utilized for securing these parts 110 to each other, if desired. Such means are shown in Figs. 1, 2 and 4 as comprising the arms or brackets 29, which pass through the holes 13, in the secondary rotors and are secured at their inner ends to the hub 20 and 115 at their outer ends to the side shell members 30 by the screws 31. The secondary rotors are provided with pockets 32 which receive these blades or pistons (see Figs. 1 and 4), the depth to which the blades enter the 120 pockets and the angular relation between the blades and the pockets varying throughout the rotation of the secondary rotors owing to the fact that the secondary rotors rotate about axes disposed at angles to the axis 125 130

of the main shaft about which the hub, shell and blades or pistons rotate. In order to provide steam-tight joints between the blades and the secondary rotors and at the same time permit of this in and out and angular movement, suitable packing means are provided, which preferably take the form of semi-cylindrical packing pieces 33 mounted in semi-cylindrical recesses 34 in the side walls of the pockets 32. The axes of the cylindrical surfaces of these packing pieces and recesses pass through the points of intersection E and F of the axes of the cylindrical surfaces with the axis of the main shaft. By this arrangement free pivotal movement of the secondary rotors upon the blades, as the system rotates, is at all times assured, the blades at the same time in no way interfering with the true rolling contact between the conical surfaces. This construction is possible because the main axis CD does not pass through the common apex O of the cones, but lies at one side of the same, thus providing the spaced intersection points E and F.

From the description thus far given, it will be seen that when the parts have rotated so that one of the blades 26 has just passed the contact line 8 between the conical surfaces, a small triangular space is formed bounded by the blade or piston and the portions of the two conical surfaces lying between the said blade or piston and the contact line. Further rotation of the parts will 35 enlarge this space and cause the blade to move away from the contact line which is a fixed position. Accordingly, it will be seen that if steam or other working fluid under pressure is admitted to this space, it 40 will act against the piston and tend to drive the same away from the fixed contact line, thus causing the engine to rotate. The force of the steam it will be seen acts directly upon the blade, which in turn is firmly anchored 45 to the shell and hub, the latter being directly mounted upon the main shaft of the engine. Thus the expansive force of the operating fluid is transmitted directly to the main shaft, from which power may be taken 50 off as desired. The main shaft, hub and shell being firmly united and at all times rotating together, may be called the "main rotor" of the engine, while the two conical members, having the rolling conical surfaces 55 and which constitute the secondary rotors, form the side walls for the working chamber. These members, however, it will be seen transmit no power and act merely as the sides of the working chamber. Thus, there 60 is no transmission of power from the blades or pistons to the secondary rotors through the engagement of the pistons with the packing pieces 33, except such slight amount as is necessary to overcome the friction of the 65 parts. It will be seen that the chamber

above referred to formed between the first piston and the portions of the conical surfaces lying between the same and the contact line 8 will continue to be thus formed and to increase in size until the blade has 70 reached a point of 180° from the contact line. At this time, if a second blade placed 180° from the first blade is employed, such second blade will pass the contact line 8 and the chamber referred to will then be bounded at each end by a portion of one of the blades and at the sides by the portions of the conical surfaces lying between the blades. The surface of the first blade exposed will, however, be greater than the surface of the 80 second blade, and the volume of the inclosed chamber will continue to increase until the first blade has rotated to a point 270° beyond the contact line, at which time the exposed areas of the two blades will become 85 equal, and no further work can be performed in the chamber lying between the two blades. At or before this point is reached, therefore, the operating fluid must be permitted to begin to exhaust from this chamber and such 90 exhaust may continue until the second blade has rotated through 270° more, and thereupon reaches the contact line 8 a second time. While the operations described are taking 95 place, however, it will be seen that a second chamber is formed as soon as the second blade first passes the contact line 8, this chamber being similar to the chamber formed when the first blade passes the contact line and being bounded by the surface 100 of the second blade and the portions of the conical surfaces lying between such blade and the contact line 8. Active work may be performed in both of the chambers between the time when the second blade first passes the contact line 8 and the time when it reaches a position 90° from such contact line, after which the exhaust is taking place from the first chamber and all of the work will 105 be performed in the second chamber until the first blade again passes the contact line 8, when the first chamber reappears as an expansion chamber. This cycle of operation, it will be seen, will repeat itself indefinitely, thus resulting in the continuous 110 115 rotation of the engine.

Any suitable means may be employed for leading the operating fluid to the working chambers and permitting the exhaust therefrom, and suitable valve mechanism may be 120 provided for governing the inlet, cut-off and exhaust and for providing for the operation of the engine in reverse direction, if desired, all as well understood in the art of fluid expansion engines. One valve mechanism 125 suitable for this purpose is shown in my Patent No. 1,091,806 above referred to. In the present case, however, I have illustrated only a very simple engine embodying the novel principle of construction herein dis- 130

closed. In this simple construction I have made no provision for variation of points of inlet, cut-off and exhaust and for reversal although it is obvious that the engine may be 5 provided with means for these purposes. As shown, the steam or other operating fluid is introduced at the left-hand end of the engine while the exhaust takes place at the right-hand end. Referring to Fig. 1, 35 is 10 an inlet passage formed in the pillar 2, this connecting with a passage 36 formed in a sleeve 37 mounted on the main shaft. The passage 36 opens into an annular passage or groove 38 preferably extending entirely 15 around the end of the sleeve 37. Mounted adjacent to the end of the sleeve 37 is a valve ring 39, which has a port 40 extending therethrough and partly around the same, the length of the port depending upon the 20 length of time during which it is desired to let steam into the working chamber. That is to say, the length of this port determines the time of inlet and cutoff. As shown—Fig. 3—, the port 40 extends halfway around 25 the valve ring. The valve ring 39 is preferably held from rotation upon the sleeve 37 by suitable means such as the pin 41 (see Fig. 3), but is permitted to have a slight longitudinal movement with reference thereto. In order to permit such longitudinal movement, while maintaining a steam-tight joint between the valve ring and sleeve, the valve ring may be provided with grooves 42, in which is placed packing 43, while 30 to. In order to permit such longitudinal movement, while maintaining a steam-tight joint between the valve ring and sleeve, the valve ring may be provided with grooves 42, in which is placed packing 43, while 35 the end of the sleeve 37 is provided with tongues 44 entering the grooves and engaging the packing. The opposite end of the ring 39 bears against the end of the hub 20, a ground joint being, preferably formed between the two. Horizontal 40 passages 45 lead from the end of the hub to the center thereof, and connect with radial passages 46, which lead to inlet port 47, opening into the chamber 25 just back of 45 each of the blades 26 (see Fig. 5). As the hub rotates, the ring 39 being stationary, it will be seen that the ends of the passages 45 will alternately come opposite to the port 40, thus permitting steam to pass through 50 the passages 45 and 46 to the chambers behind the blades. When the proper amount of rotation has taken place, however, the ends of passages 45 will pass the end of the port 40 and then the ingress of steam will 55 be cut off. Exhaust takes place through ports 48 located similarly to the ports 47, but at the opposite sides of the blades, the ports 48 being connected by radial passages 49 and horizontal passages 50 (see dotted 60 lines in Fig. 4) with an exhaust port 51 (see Figs. 4 and 6) formed in a ring 52 which is mounted adjacent to the end of a sleeve 53 having an exhaust passage 54 therein. The construction of the ring 52 and 65 sleeve 53 is similar to the construction of

the inlet ring and sleeve except that the port 51 preferably is somewhat longer than the port 40 in the ring 39 so as to provide for exhaust taking place during 270° of rotation. Thus, it will be seen that in the simple form 70 of engine illustrated an automatic valve construction is provided in which the rotation of the main rotor itself accomplishes the opening and closing of the inlet and exhaust ports. 75

In order to provide an engine in which pressures are balanced, as far as possible, I prefer to provide means for permitting the pressure of the operating fluid to act upon the backs of the secondary rotors 6 so as to 80 maintain these rotors so far as possible in a balanced condition, and thus relieve in great part the thrust transmitted to the bearings 5. For this purpose I admit steam pressure to the spaces 55 formed between the backs of 85 the ring-portions of the secondary rotors 6, and the side portions 30 of the outer shell. The portions 30 are preferably recessed, as indicated at 56, so as to extend the spaces throughout the entire circumference of the 90 rotors. Steam is admitted to these spaces through suitable horizontal ducts 57 which communicate with the ports 40 in the ring 39, said horizontal ducts being connected with the spaces by means of the radial ducts 95 58 which preferably extend along side of the edges of the blades or pistons (see Fig. 4). Any other suitable way of introducing fluid pressure to the spaces back of the rotors may be employed if desired. As the 100 pressures to which the conical surfaces of the secondary rotors and the areas of such surfaces exposed to active steam pressure vary during the cycle of operations, it is not possible to balance these pressures exactly, 105 but the areas of the backs of the secondary rotors exposed to the steam pressure in the chambers 55 are made of such size that the pressure acting thereon is slightly greater than the maximum pressures to which the 110 conical surfaces of the rotors are subjected. Thus the rotors are slightly overbalanced and the conical surfaces held in firm contact along the line 8 by this over-balanced pressure. The rotors are however compelled to 115 rotate about their predetermined axes of rotation by their engagement with the spherical surfaces of the hub and shell, and with the thrust bearings 5.

If desired, the contact surfaces between 120 the secondary rotors and the hub and shell, respectively, may be packed in any suitable manner, as by means of the packing rings 59 and 60 held in grooves formed in the secondary rotors, as shown in Fig. 1.

The engine illustrated in the drawings and particularly described in the foregoing specification is merely an illustration of a simple, preferred construction in which my invention may be embodied; and I do not 130

wish to be understood as limiting myself in any way to such embodiment or to particular structural features any further than is set forth in the appended claims. My engine is capable of modification and elaboration in many respects, and in many cases, particularly for engines of large power, various changes may be made, for example, the engine may be constructed with concentric working chambers, two sets of rolling conical surfaces being provided, and sets of blades in staggered relation being employed as covered by my Patent No. 1,091,806. Obviously, also, it may be compounded or built up with multiple units, while the details of construction may be freely changed to suit the conditions of use, or the judgment of the constructor.

Having thus described my invention, I claim:—

1. In a rotary engine, the combination of a main rotor, and secondary rotors having conical surfaces rolling in contact and coöperating with parts of said main rotor to form a working chamber, the axes of the conical surfaces of said secondary rotors intersecting the axis of rotation of said main rotor at spaced points, and an abutment rotating with said rotors and forming a wall of the working chamber.

2. In a rotary engine, the combination of a main rotor, secondary rotors having conical surfaces rolling in contact and an abutment, said secondary rotors and abutment coöperating with parts of said main rotor to form a working chamber, the cones in which the conical surfaces of said secondary rotors lie having a common apex located at one side of the axis of rotation of said main rotor.

3. In a rotary engine, the combination of a main rotor having parts forming the inner and outer walls of a working chamber, a rigid piston extending across said working chamber rigidly and immovably connected to said main rotor, and a pair of secondary rotors associated with said main rotor and having conical surfaces rolling in contact which form the side walls of said working chamber.

4. In a rotary engine, the combination of a main rotor having parts forming the inner and outer walls of a working chamber, a piston extending across said working chamber and rigidly connected to said main rotor, a pair of secondary rotors associated with said main rotor and having conical surfaces rolling in contact which form the side walls of said working chamber, and sliding and pivotal joints between said secondary rotors and said piston, the pivotal axes of said joints passing through the points of intersection of the axes of the conical surfaces of said secondary rotors with the axis of rotation of the main rotor.

5. In a rotary engine, the combination of a hub having two adjacent spherical surfaces, the centers of which lie in a common axis, a pair of rotors having conical surfaces rolling in contact, one of said rotors being movably mounted on each of said spherical surfaces, a piston extending between said rotors, and an inclosing shell, inclosing a working chamber between said rotors, portions of the conical surfaces of said rotors and said piston forming walls of said working chamber.

6. In a rotary engine, the combination of a shell having two adjacent spherical surfaces, the centers of which lie in a common axis, a pair of rotors having conical surfaces rolling in contact, one of said rotors being movably mounted in each of said spherical surfaces, and a piston extending between said rotors, portions of said conical surfaces, said piston, and said spherical surfaces forming walls of a working chamber.

7. In a rotary engine, the combination of a pair of rotors having conical surfaces rolling in contact and a shell inclosing said rotors, said shell having a pair of concave spherical surfaces fitting the respective rotors, said conical and spherical surfaces forming walls of a working chamber, the conical surfaces of said rotors lying in cones having a common apex, the centers of said spherical surfaces lying in the axes of said cones at points spaced from the common apex thereof, and a piston extending between said conical rotors.

8. In a rotary engine, the combination of a main rotor, a piston carried thereby, a pair of secondary rotors associated with said main rotor and having conical surfaces rolling in contact, pivotal and sliding joints between said piston and said secondary rotors, the pivotal axes of said joints at all times passing through the main axis of rotation of said main rotor and through the axes of rotation of the respective secondary rotors.

9. In a rotary engine, the combination of a main rotor including a hub having a pair of convex spherical surfaces thereon and a shell having a pair of concave spherical surfaces concentric with the respective surfaces of said hub, said concentric surfaces of said hub and shell forming the inner and outer walls, respectively, of a working chamber, one or more pistons carried by said hub and shell and adapted to cross said working chamber, a pair of secondary rotors associated with said main rotor and having conical surfaces rolling in contact and having spherical surfaces fitting the respective spherical surfaces of said hub and shell, the centers of the respective pairs of concentric surfaces of said hub and shell coinciding with the points of inter-

section of the axes of rotation of said secondary rotors with the axis of rotation of said main rotor.

10. In a rotary engine, the combination 5 of a main rotor including a hub having a pair of convex spherical surfaces thereon, a shell having a pair of concave spherical surfaces concentric with the respective surfaces of said hub, said concentric surfaces 10 of said hub and shell forming the inner and outer walls, respectively, of a working chamber, one or more pistons carried by said hub and shell and adapted to cross said working chamber, a pair of secondary 15 rotors associated with said main rotor and having conical surfaces rolling in contact and having spherical surfaces fitting the respective spherical surfaces of said hub and shell, the centers of the respective pairs of 20 concentric surfaces of said hub and shell coinciding with the points of intersection of the axes of rotation of said secondary rotors with the axis of rotation of said main rotor, and pivotal and sliding joints 25 between said secondary rotors and said pistons, the pivotal axes of said joints passing through the respective points of intersection.

11. In a rotary engine, the combination 30 of a main rotor including a hub having a pair of convex spherical surfaces thereon, a shell having a pair of concave spherical surfaces concentric with the respective surfaces of said hub, said concentric surfaces 35 of said hub and shell forming the inner and outer walls, respectively, of a working chamber, one or more pistons carried by said hub and shell and adapted to cross said working chamber, a pair of secondary 40 rotors associated with said main rotor and having conical surfaces rolling in contact and having spherical surfaces fitting the respective spherical surfaces of said hub and shell, the centers of the respective pairs 45 of concentric surfaces of said hub and shell coinciding with the points of intersection of the axes of rotation of said secondary rotors with the axis of rotation of said main rotor and thrust bearings for said 50 secondary rotors.

12. In a rotary engine, the combination of a pair of rotors having conical surfaces

rolling in contact, said conical surfaces forming walls of a working chamber, a shell inclosing said rotors, and forming another wall of said working chamber, a piston crossing said working chamber, and means for admitting fluid pressure into said shell in the rear of said rotors to hold said rolling conical surfaces in contact. 55

13. In a rotary engine, the combination 60 of a main rotor including a hub and a shell, a pair of secondary rotors associated with said main rotor and having ring-shaped portions fitting between said hub and shell, said secondary rotors having conical surfaces rolling in contact, said 65 conical surfaces and portions of said hub and shell inclosing a working chamber, a piston crossing said working chamber, and means for admitting fluid pressure into said shell behind the rear surfaces of said ring-shaped portions whereby said pressure acts 70 to hold the rolling conical surfaces of said 75 secondary rotors in contact, the total pressure acting on the rear surfaces of said ring-shaped portions being greater than the total maximum pressure which can act upon 80 said rolling conical surfaces. 80

14. In a rotary engine, the combination 85 of a hub, a shell, secondary rotors mounted between said hub and shell and having conical surfaces rolling in contact, portions of said secondary rotors projecting beyond said hub and shell, bearings engaging said projecting portions of said secondary rotors, said projecting portions having transverse openings therethrough, connecting 90 members uniting said hub and shell and passing through said openings, and a piston extending between said hub and shell and said secondary rotors. 90

15. In a rotary engine, the combination 95 of a main rotor, including a hub and inclosing shell, a pair of secondary rotors having conical surfaces rolling in contact and cooperating with said main rotor hub and shell to form a working chamber, a piston crossing said working chamber, and 100 ports in said hub opening into said working chamber. 100

FRANS IVAR L. BYLGER.
